UNITED STATES PATENT OFFICE.

ROSS DE SIMONE, OF HILTON, NEW YORK.

PNEUMATIC RAILWAY-GATE.

1,388,101.

Specification of Letters Patent. Patented Aug. 16, 1921.

Application filed September 27, 1919. Serial No. 326,967.

To all whom it may concern:

Be it known that I, Ross De Simone, a citizen of the United States, residing at Hilton, in the county of Monroe and State 5 of New York, have invented new and useful Improvements in Pneumatic Railway-Gates, of which the following is a specification.

The present invention relates to automatic railway gates.

In carrying out my invention it is my purpose to produce a gate for railway crossings which shall be automatically operated by suitable mechanism actuated by a train 15 approaching the crossing for bringing the gate to obstructing position, while weighted means automatically return the gate to unobstructing position after the train has passed the crossing.

20 It is also my purpose to produce a device of this character which shall be of an extremely simple construction, positive in actuation and sure in operation.

Other objects and advantages will present themselves as the nature of the invention is better understood, reference being had to the accompanying drawings, in which:

Figure 1 is a plan view of a railway crossing provided with gates operated in accordance with this invention, said gates being in obstructing closed position.

Fig. 2 is a side elevation of the same.

Fig. 3 is an enlarged sectional view on 35 the line 3—3 of Fig. 1.

Fig. 4 is an enlarged vertical sectional view on the line 4—4 of Fig. 1.

Fig. 5 is a horizontal sectional view of the semaphore operating cylinder.

40 Referring to the drawings in detail, 10 represents a railway track, the crossing of which being protected by gates 11 and 12 respectively. These gates are pivotally secured upon suitable supports 13 which, in 45 the present instance, are in the nature of casings. The gates have their lower ends weighted in the usual manner whereby the same are normally retained in a vertical position, suitable stop means 14 being provided for contacting with the gates for holding the same in such vertical or non-obstructing position.

One pair of the gates 11 and 12 is disposed to the opposite sides of the tracks at 55 the crossing.

Arranged between the rails of the track,

at a suitable distance from each side of the crossing are the spaced cylinders or body members 15 of air compressing pumps. Only one series of such pumps has been illustrated by the drawings, but it is to be understood that the construction and operation of each series is similar. The cylinders are arranged one directly forward of the other, and each has therein a plunger 16 which is influenced by a spring 18 to move the same toward the top or head of the cylinder. Each plunger 16 is provided with a stem 17 that passes through a suitable stuffing box in the head of the cylinder and each stem has its outer end provided with a round head 19. Each cylinder is provided with an air bleed port 15'. The cylinders have their base portions or heads connected by short pipes and couplings to the air conducting pipe 20 which leads to a reservoir 21. On the train (not shown) there is a suitable depending element in the path of contact with the heads 19, and such contact will successively depress the plungers in 80 the respective casings, compressing air therein and forcing such compressed air through the pipe 20, and into the reservoir 21. From the reservoir there is a pipe 22 that communicates with a cylinder 23 in 85 which there is arranged a piston 24 that has its stem 24' projecting through the sleeve and has a pin 24'' passing through a slot 25' in the end of an arm or lever 25. The lever is keyed or otherwise secured to a 90 shaft on which there is a signal or semaphore arm 25'.

Also leading from the reservoir 21 is an air conducting pipe 26 that connects directly with the cylinder 26' in one of the 95 casings 13 and with a branch pipe connecting with a similar cylinder 26' in the opposite casing 13 to which the second gate 11 is pivotally connected. Each of the cylinders 26' is provided with a suitable bleed 100 port, and in each of the said cylinders there is a piston 27 that has its stem 28 projecting through a packing box in the head of the cylinder. Each piston stem 28 has loosely 105 connected to the outer arm thereof a link 28' that in turn is connected to the free end of a crank 29 that is keyed or otherwise secured on the shaft 30 that provides the pivots for the respective gates 11—12.

The reservoir 21 has an exhaust safety valve 110 31 connected therewith. The successive downward movement of the plungers in the air

pumps will, as previously stated, force compressed into the reservoir 21 which from there will be delivered through the pipes 22 and 26 to operate the semaphore arm 5 and the gates. A surplus amount of the air will be exhausted through the safety valve in the cylinder, and the compressed air will be exhausted through the bleed ports in the cylinders 26' and the pump cylinders 16, 10 after the train has passed the crossing. The gates are returned to unobstructing position through the medium of the weights associated therewith, but such return is slowly accomplished as the bleed ports are comparatively small and some time is required 15 before the air is fully exhausted from the cylinders. This is really an advantage, inasmuch as the pumps or air compressors are located a considerable distance away from 20 the crossing, and the train fully passes over the crossing before the gates are brought to non-obstructing position.

It will be apparent that air forced from the cylinders that provide the pumps into 25 the reservoir 21 will be distributed so as to operate the gates as well as the semaphores on each side of the crossing. After the train has passed the crossing sufficient air will have been permitted to escape from the cylinder 30 21 to allow the weighted gates and semaphores to descend, as a matter of fact the said weights on the gates and semaphores affecting and ejecting the air from the reservoir and from the pistons. While 35 the device, as above described, is devised for a one-way track, in which a train travels in only one direction, it will be apparent that by slight alterations the arrangement may be so changed as to permit the gates 40 and semaphores being operated from trains

passing in opposite directions, either upon one or a plurality of tracks.

Having thus described the invention, what is claimed as new, is:—

In combination with the rails of a track, 45 a crossing, pivotally supported weight influenced gates at the crossing and a signal carrying shaft to one side of the gates, of pneumatic means for operating the gates to an obstructing position and for revolving 50 the shaft to bring the signal thereon to signaling position, including air compressing pumps disposed one forward of the other between the rails of the track, to the sides 55 of the crossing, each of said pumps including a cylinder having an air bleed port, a plunger in the cylinder spring influenced toward the top of the cylinder, a stem for the plunger passing through the cylinder and a rounded head for the stem, and the 60 said rounded heads being in the path of engagement with a contact element on a train approaching the crossing, a reservoir 65 having a safety valve and having a pipe connection with the respective cylinders, 70 pipes leading from the reservoir, a cylinder with which one of said pipes communicates, a piston therein, a stem for the piston passing through the cylinder, a slotted rod connected with the shaft of the signal arm 75 freely receiving the end of the stem in the slot thereof, cylinders having bleed ports with which the second pipe communicates, pistons therein, rods therefor projecting through the cylinders, links pivotally connected to the rods, and a crank on the pivot of the respective gates to which said links are pivoted.

In testimony whereof I affix my signature.
ROSS DE SIMONE.
